UNITED STATES PATENT OFFICE.

FRANCIS WILLIAM CROSSLEY, OF MANCHESTER, AND JAMES ATKINSON,
OF AMHERST, FALLOWFIELD, ENGLAND.

GAS OR OIL MOTOR ENGINE.

SPECIFICATION forming part of Letters Patent No. 555,898, dated March 3, 1896.

Application filed August 21, 1894. Serial No. 520,944. (No model.) Patented in England September 8, 1893, No. 16,900, and in France February 5, 1894, No. 236,061.

To all whom it may concern:

Be it known that we, FRANCIS WILLIAM CROSSLEY, a resident of Ancoats, Manchester, and JAMES ATKINSON, a resident of Amherst, Fallowfield, England, subjects of the Queen of Great Britain, have invented certain new and useful Improvements in Gas or Oil Motor Engines, (patented in England September 8, 1893, No. 16,900, and in France February 5, 1894, No. 236,061,) of which the following is a specification.

Our invention relates to gas and oil motor engines which work on what is known as the "Otto" cycle—that is to say, the piston, in its outstroke, draws combustible charge into the cylinder. In its instroke it compresses the charge; through its next outstroke it is propelled by the pressure of the ignited charge, and through the succeeding instroke it expels the products of combustion. There is necessarily a space for charge in the cylinder behind the piston at the extreme of its instroke, which space, as such engines are usually constructed and worked, remains full of residuary products of combustion at the end of the expelling stroke, and as the fresh combustible charge has to mix with these its capability of being ignited and its efficiency as working fluid are seriously impaired, particularly when gases or vapors of comparatively low combustibility are employed. Various methods have been proposed to remedy this defect—as, for instance, by pumping in air or pumping out the products of combustion.

Our invention relates to novel means of thoroughly clearing out the residuary products of combustion from the charge-space of the cylinder and filling that space with pure air or combustible mixture during the first portion of each charging stroke. We effect this as we shall describe, referring to the accompanying drawings.

Figure 1 is an end view of the cylinder of a gas or oil motor engine arranged to operate according to our invention. Fig. 2 is a longitudinal section of the rear part of the cylinder on the line Y Y, Fig. 4. Fig. 3 is a transverse section on the line X X of Fig. 4, which is a sectional plan on the line 1 1, Fig. 1.

The piston G, which in Figs. 2 and 4 is shown at the extreme of its instroke, is by preference made concave on its face, and the

rear end of the cylinder is likewise made concave, so that the space A behind the piston is of such form that gaseous fluid can sweep readily and uniformly through it, as indicated by the arrows. 55

B is the valve by which, when it is open, air, or air mixed with combustible gas or vapor, can enter the space A through a passage which at H is gradually narrowed in plan and heightened in elevation, so that the fluid passing in shall spread uniformly through the space A. 60

M is the gas-valve. 65

From the space A a passage leads to the exhaust-valve C, this passage being at E gradually widened in plan and lowered in elevation, the reverse of inlet-passage H, so that fluid shall readily and uniformly pass through and out from the space A behind the piston. The exhaust-pipe F (shown in Figs. 1 and 3 as extending from the exhaust-valve C) is made of considerable length. The length of the exhaust-pipe, however, is of importance. It is controlled to some extent by the speed at which the engine runs. At speeds commonly used we find a length of about sixty feet gives the best results, and in this length there should be no chamber of any material capacity, such as a large exhaust-box. Small exhaust-boxes may be used without materially affecting the result, and also silencing apparatus, such as chambers containing gravel, may be used at the end of the exhaust-pipe. If the engine runs faster a shorter length will suffice; if slower a longer length is necessary. 70 75 80

The purpose of the long exhaust-pipe we shall presently explain in describing the operation of the engine. 90

The air-valve B, exhaust-valve C and gas-valve M are shown as operated by double-ended levers k, l and M', which, as indicated, are hung in suitable bearings connected with the engine, and at one of their ends they each engage the valve-stems C', b and m of their respective valves, while at their other extremities they are each provided with a friction-roller L', m' and k'. These (the air, exhaust, and gas levers) are actuated to operate their respective valves by means of cams K, L and L" upon the shaft J, the said cams being arranged to engage the friction-rollers on the said valve-levers in their rotation and at the desired 95 100

times. The cam-shaft J is mounted in suitable bearings alongside the cylinder G and arranged to be driven at half the speed of the crank-shaft.

- 5 The mechanical connections here illustrated show one of the many ways in which the valves of the engine may be operated; but we do not limit ourselves thereto, as they may be modified without departing from our invention, as 10 will be understood by those skilled in the art.

We so adjust the cam or other gear which works the exhaust-valve C that it is opened some time before the piston reaches the end of the propelling outstroke in the ordinary 15 manner that it is kept open during the whole of the expelling instroke, and also during the earlier part of the charging stroke until the crank has moved about forty-five degrees past its center. Also when the charging- 20 valve B is worked by the engine we arrange the gear so that it shall be opened before the piston has completed its expelling instroke—that is to say, while the crank has some forty-five degrees to move before this instroke is 25 completed. In some cases, however, the charging-valve B need not be worked by the engine but left to open and close automatically. These adjustments being made, the 30 operation is as follows: Toward the end of the propelling outstroke, when the gases in the cylinder are at considerable pressure, the exhaust-valve C is opened and a rapid out-rush of gases takes place, putting in motion the long column of gaseous fluid in the ex- 35 haust-pipe F. The momentum of this column causes a rapid reduction of pressure in the cylinder, so that while the piston is approaching the end of its instroke and beginning its charging outstroke fresh air rushes past the 40 valve B into the cylinder, effectually clearing out the residuary products of combustion from the space A, which is thus left charged with pure air ready to receive the combustible gas or vapor which may be introduced as 45 the piston continues its charging outstroke. The timing of the exhaust and charging valves mentioned are suitable for normal speeds. When these are exceeded the exhaust-valve may be held open for a still greater proportion 50 of the charging stroke.

The shape of the cylinder end and the positions of the valves may be varied to suit circumstances. It is, however, essential that they must be such as to enable gases to pass 55 uniformly through from the charging-valve B to the exhaust-valve C. The length of the exhaust-pipe may also be varied so long as its proportions conform to the principles set forth.

60 We do not limit ourselves to the mechanical details shown and described by way of illustration, as they may be modified in many particulars without departing from the invention.

65 What we claim is—

1. A gas or oil motor engine having its cylinder provided with a charging-space in rear

of its piston and formed with extended inlet and exhaust openings, said openings extending respectively into and from the charging-space and respectively gradually narrowed in plan and heightened in elevation, and widened in plan and lowered in elevation as they merge with the charging-space, whereby the inrushing air entering through the inlet-opening will be deflected and sweep uniformly through the charging-space to the exhaust-valve. 70

2. A gas or oil motor engine having its cylinder provided with a charging-space in rear of its piston said space formed with extended inlet and exhaust openings, said openings being respectively gradually narrowed in plan and heightened in elevation, and widened in plan and lowered in elevation as they merge 75 with the charging-space, whereby the inrushing air entering through the inlet-opening will be deflected and pass uniformly through the charging-space to the exhaust-valve in combination with an exhaust-pipe. 80

3. A gas or oil motor engine having its cylinder provided with a charging-space in rear of its piston and formed with extended inlet and exhaust openings on opposite sides of the charging-space, said openings being respectively gradually narrowed in plan and heightened in elevation, and widened in plan and lowered in elevation as they merge with the charging-space and an exhaust-pipe extending 90 from the exhaust-opening. 95

4. A gas or oil motor engine having the rear end of its cylinder and of its piston arranged to form a spheroidal charging-space, said cylinder being provided with inlet and outlet openings on approximately opposite sides of the charging-space, said openings being respectively gradually narrowed in plan and heightened in elevation and widened in plan and lowered in elevation as they merge with the charging-space, an exhaust-pipe and suitable valves and valve-operating mechanism controlling the inlet and outlet openings. 100

5. A gas or oil motor engine having a cylinder formed with a charging-space at its rear end, inlet and exhaust openings merging with 115 the charging-space, an exhaust-pipe, means for opening the exhaust-valve as is usual before the completion of the propelling stroke thereby imparting motion to the column of gases in the exhaust-pipe thus rapidly reducing the cylinder-pressure, and means for keeping open both exhaust and inlet valves until the piston has traversed a portion of its outward charging stroke. 120

6. In a gas or oil motor engine a cylinder 12, and piston arranged to have a charging-space between their rear ends when piston is at full instroke, inlet and exhaust openings into the charging-space, an exhaust-pipe and means for opening as is usual the exhaust before completion of power stroke, and by escape of gases forcibly starting into outward motion the column in the exhaust-pipe, and for keeping said valve open during part of 130

the succeeding charging outstroke, and means also for opening the air-valve before the completion of the expelling instroke and for keeping it open also during the first part of the 5 charging outstroke.

7. In a gas and oil motor engine, a cylinder having a charging-space at its rear end, inlet and exhaust ports, an exhaust-pipe and means for opening and closing said ports 10 and for keeping them both open simultaneously during a portion of the exhaust instroke and of the charging outstroke.

8. In a gas and oil motor engine, the combination with the cylinder having a charging-space, of suitable inlet and exhaust valves and 15

an exhaust-pipe, the same having such length and capacity that when its column of gases is started outward on the opening of the exhaust-valve by the outrushing of the gases in the cylinder, the momentum thereof will 20 rapidly withdraw the contents of the cylinder and also draw fresh air therethrough.

In testimony that we claim the foregoing as our invention we have signed our names in presence of two witnesses.

FRANCIS WILLIAM CROSSLEY.

JAMES ATKINSON.
